CLAIM

The ornamental design for a wheel for motor vehicle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a wheel for motor vehicle showing my new design;

FIG. 2 is a front view thereof; and,

FIG. 3 is a side view thereof.

The broken lines illustrate portions of the wheel for motor vehicle and form no part of the claimed design.
